UNITED STATES PATENT OFFICE.

CHARLES W. KOHLMANN, OF BALTIMORE, MARYLAND.

BELT AND GARMENT SUPPORTER.

SPECIFICATION forming part of Letters Patent No. 720,591, dated February 17, 1903.

Application filed May 31, 1902. Serial No. 109,672. (No model.)

To all whom it may concern:

Be it known that I, CHARLES W. KOHLMANN, a citizen of the United States, residing in Baltimore, State of Maryland, have invented 55
certain new and useful Improvements in
Belt and Garment Supporters, of which the
following is a specification.

One object of my invention is to provide a
device adapted to be applied to a belt which
10 shall serve to connect the belt with the waist-
band of trousers or drawers in such manner
that the belt and waistband shall mutually
support each other, the trousers or drawers, or
both, being held up in proper position by the
15 belt, while the belt is retained in proper position
around the waistband.

Another object of my invention is to provide
an improved device for supporting articles
20 such as chatelaines, &c., from a belt or
stockings from the waistband of a nether garment.

In carrying out my invention I employ a
clasp consisting of a body portion having at
25 its upper end a hook adapted to extend over
and embrace the upper edge of the waist-
band and at its lower end a hook adapted to
receive the lower edge of a belt. The body
portion is provided with a spring-tongue,
30 which is connected thereto near its lower end
and which has an upper free end located
when in use within the hook and which is
adapted to engage with the upper edge of the
waistband within the hook. This spring-
35 tongue is normally flush with the body portion,
or substantially so—*i. e.*, it lies substantially
in the same vertical plane therewith—
so that its upper garment-engaging end is with-
drawn from the space within the hook, allowing
40 the hook to be readily placed over the
waistband. The upper end of the tongue may,
however, be moved inward, so as to grip the
waistband, by means of a lever pivoted to
the body portion, having an arm engaging
45 the tongue close to its upper end and a longer
arm outside the body portion, by means of
which it may be operated. The lower end of
the lever may be provided with a catch adapted
50 to engage the lower hook of the body portion;
but when the device is adapted to sus-
pend chatelaines, &c., from a belt or hose-
supporter from a waistband or belt the catch
is omitted, and instead of forming the lower

end of the body portion with a hook it is
formed with a slot to receive the suspending-
strap or chains of the hose-supporter or chate- 55
laine.

In the accompanying drawings, Figure 1
shows a front elevation of my device applied
to a belt and a pair of trousers, only so much
of the belt and trousers being shown as is 60
necessary to illustrate how the device is used.
Fig. 2 is a detail view showing the preferred
manner of providing the body portion with a
spring garment-engaging tongue. Fig. 3 is
a side elevation, on an enlarged scale, of the 65
device, the operating-lever being raised and
the garment-engaging tongue being with-
drawn from its engaging position. Fig. 4
shows a transverse section on the line 4-4 of
Fig. 1. Fig. 5 shows a side elevation of the 70
device adapted for use in connection with
chatelaines and the like or hose-supporters.
Fig. 6 is a front elevation of the device shown
in Fig. 5.

Referring first to Figs. 1 to 4, inclusive, the 75
body portion *a* is shown as formed at its up-
per end with a hook *b* and at its lower end
with a hook *c*. The hook *b* is adapted to ex-
tend over the top of the waistband *A* of a
pair of trousers or drawers, or both, while 80
the lower hook is adapted to extend under
the bottom of a belt *B*. The body portion is
provided with a tongue *d*, the upper end of
which is located when in use within the up-
per hook *b* and is adapted to engage the waist- 85
band in the manner shown in Fig. 4. Prefer-
ably the tongue is formed in one piece with
the body portion in the manner indicated in
Fig. 2; but it might be a separate piece se-
cured to the body portion, as illustrated in 90
Figs. 5 and 6. In either case I prefer that
the tongue shall be a spring-tongue attached
to or connected with the body portion near
its lower end and free to move at its upper
end into the upper hook when positively ac- 95
tuated for this purpose. Normally the tongue
d lies in the same vertical plane with the
body portion, so as to leave the upper hook
open, as shown in Fig. 3; but when the device
is applied to the trousers the engaging end 100
of the tongue is forced into the hook by a
lever *e*, pivoted to the body portion near its
upper end, having a short arm *f*, adapted to
engage the upper end of the tongue close to

its garment-gripping end, and a longer arm *g*, which when the device is closed reaches to the lower hook *c* and preferably engages therewith by means of a catch, which may be 5 a stud *h* on the lever, adapted to connect with the upper edge of the hook. The belt *B* is inclosed by the body portion, the lever, and the lower hook and is prevented from moving up or down, being always held in the 10 same position relatively to the waistband.

In applying the device the upper hook is first placed over the top of the waistband when the parts of the clasp are in the position shown in Fig. 3. The belt is then placed in 15 position with its lower edge in the lower hook *c*, and the lever is then depressed to the position shown in Fig. 4. When this is done, the upper end of the tongue will be made to take a firm hold on the waistband, while the 20 belt will be inclosed and held in proper position by the longer arm of the lever.

My improved device is adapted to engage the waistband near its upper edge, thus holding the waistband, as well as the other parts 25 of the garments, erect and smooth. The lever engages the tongue close to its gripping end, thus pressing it firmly into place and securely holding it in engagement with the waistband, and as the waistband has its extreme upper edge at the top of the hook it 30 will be caused to spread slightly above the end of the tongue, and thus afford a means for preventing disengagement of the parts. The device is compact, may be made in only 35 two parts—viz., the body portion, the tongue—and the hooks forming one part and the lever the other part. It is reliable in use and may be readily applied or removed.

When the device is adapted for use in connection with chatelaines, &c., or hose-supporters, the lower hook is omitted, as shown in Figs. 5 and 6, and the lower end of the body portion is formed with a slot *i* to receive the strap or chain *H*. In Figs. 5 and 6 I have 45 shown the tongue as being formed of a separate piece of metal and secured to the body portion; but it may be formed integrally therewith in the manner indicated in Figs. 1 to 4, inclusive. It is essential that the tongue 50 should bend inward at its upper end; but so far as some features of my invention are concerned it is immaterial whether the tongue is pivoted at its lower end, secured at this end to the body portion, or is formed in one piece 55 therewith. I prefer, however, to always make the tongue a spring-tongue, so that when the lever is raised the tongue will withdraw from the hook and leave it free to receive the waistband or belt. Any preferred number of clasps 60 may be employed. Where the device is adapted for use as a hose-supporter, two clasps are used. Where the device is used for connecting a belt with a pair of trousers, two or more may be used. The device shown in Figs. 5

and 6 may be applied to the waistband of any 65 garment or to a suitable belt.

I claim as my invention—

1. A clasp comprising a body portion formed at its upper end with a hook, a tongue on the body portion normally outside the hook and 70 having its upper end arranged close to the upper end of the hook, and a lever pivoted to the body portion near its upper end and having an arm engaging the tongue close to the upper, gripping end thereof and which moves 75 the tongue into the hook.

2. A clasp adapted to attach a waistband to a belt, comprising a body portion formed at its upper end with a hook adapted to pass over the upper edge of the waistband, a tongue 80 on the body portion normally outside the hook and having its upper end arranged close to the upper end of the hook, and a lever pivoted to the body portion near its upper end and having an arm engaging the tongue close 85 to the end thereof which grips the waistband.

3. A clasp adapted to connect a waistband to a belt, comprising a body portion formed at its upper end with a hook adapted to pass over the upper edge of the waistband, a spring- 90 tongue on the body portion normally outside the hook and having its upper end arranged close to the upper end of the hook, and a lever pivoted to the body portion near its upper end, and having an arm engaging the tongue 95 close to the end thereof which grips the waistband and which moves the spring-tongue into the hook.

4. A clasp adapted to connect a waistband to a belt, comprising a body portion formed 100 at its upper end with a hook adapted to pass over the upper edge of a waistband and at its lower end with a hook adapted to embrace the lower edge of a belt, a tongue on the body portion normally outside the hook and having 105 its upper end arranged close to the upper end of the hook, and a lever pivoted to the body portion near its upper end, and having an arm engaging the tongue close to the end thereof which grips the waistband. 110

5. A clasp adapted to connect a waistband to a belt, comprising a body portion formed at its upper end with a hook adapted to pass over the upper edge of the waistband, and at its lower end with a hook adapted to embrace 115 the lower edge of the belt, a tongue on the body portion having its upper end arranged close to the upper end of the hook, and a lever pivoted to the body portion near its upper end having an arm engaging the tongue close 120 to the end which grips the waistband and provided with a catch engaging the lower hook.

In testimony whereof I have hereunto subscribed my name.

CHARLES W. KOHLMANN.
